(57) **CLAIM**

The ornamental design for coin box printer for gaming device, as shown and described.

DESCRIPTION

FIG. 1 is a perspective view of a coin box printer for gaming device showing our new design; shown in its environmental use;

FIG. 2 is an enlarged scale perspective view of a coin box printer for gaming device; and,

FIG. 3 is a front elevational view of FIG. 2.

The broken lines are for illustrative purpose only and forms no part of the claimed design.
